W. E. WALKER.
CARD RAISING ATTACHMENT FOR FILING DRAWERS.
APPLICATION FILED MAY 7, 1919.

1,380,612.

Patented June 7, 1921.

Inventor

William F. Walker.

Attorney

UNITED STATES PATENT OFFICE.

WILLIAM E. WALKER, OF DENVER, COLORADO.

CARD-RAISING ATTACHMENT FOR FILING-DRAWERS.

1,380,612.

Specification of Letters Patent. Patented June 7, 1921.

Application filed May 7, 1919. Serial No. 295,366.

To all whom it may concern:

Be it known that I, WILLIAM E. WALKER, a citizen of the United States, residing at the city and county of Denver and State of Colorado, have invented certain new and useful Improvements in Card-Raising Attachments for Filing-Drawers; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates broadly to improvements in filing drawers or boxes, and more specifically to an attachment therefor for raising the cards employed in such drawers in order to facilitate the removal of a card or cards from any desired part of the drawer. It is well known that there is considerable difficulty in removing a card from a filing drawer of this kind where the cards are all on the same level, as the cards are usually pressed together with considerable force, making the separation of the desired card troublesome.

My improvement consists in providing means adjustable in the bottom of the drawer for raising a number of cards from any desired location in the drawer in order that the desired card or cards may be easily obtained.

The device consists of a small frame, guided and longitudinally slidable in the lower part of the box, this frame being actuated and controlled by a stem or rod which is exposed at the front end of the box and is rotatably mounted, the portion of the rod connected with the frame having a crank arm which, when the rod is given a partial rotation, acts upon a plate hingedly connected with the frame, to tilt the plate and impart a corresponding upward movement to the cards immediately above the plate.

Having briefly outlined my improvement, I will proceed to describe the same in detail, reference being made to the accompanying drawing, in which is illustrated an embodiment thereof. In this drawing:

Figure 1 is a side elevation of a filing drawer equipped with my improvement.

Fig. 2 is a similar view, with one side of the box partly broken away, and showing

the improvement in the card-raising position.

Figs. 3 and 4 are fragmentary detail views of the device shown in connection with the guides for the frame.

Fig. 5 is a top plan view of the construction shown in Figs. 3 and 4, the hinged plate being partly broken away.

Fig. 6 is a section taken through the drawer, illustrating a follower located in the rear of the cards, the follower being shown in connection with the card-raising attachment.

The same reference characters indicate the same parts in all the views.

Let the numeral 5 designate a filing drawer adapted to hold a series of cards, 6, separated by dividers 7, in the usual manner. Below the cards, and on each side of the box, is located a strip 8, grooved as shown at 9, the said grooved strips being adapted to receive lugs, 10, with which the rear portion of a triangular-shaped wire frame 12 is provided. This frame is composed of a transverse member 13, and two forwardly projecting members, 14, which approach each other and are merged in the reinforced forward extremity 15 of the frame. A rod 16 is journaled in this frame and passes through a perforation in the part 15, and also in the transverse member 13, which is also reinforced for the purpose. The forward portion of the rod passes through an opening in the front end of the drawer and is slidable therein. The rod 16, between the points where it is journaled in the wire frame, is formed into a crank arm 17, while a lifting plate 18 is hingedly connected with the frame member 13, as shown at 19, the said plate being preferably of triangular shape, and when in the down position, concealing the wire frame in plan view.

As the frame 12 is freely slidable in the drawer, it is evident that the frame may be moved to any desired position for the purpose of raising a portion of the cards, this operation being accomplished by imparting a partial rotary movement to the part 16, whereby the crank arm 17 is caused to act on the plate 18 from below to lift the plate or tilt it upwardly from its rear extremity, where it is hinged to the frame.

As the rod or stem 16 takes the place of the usual guide rod for the follower in drawers of this character, it becomes neces-

sary to provide a special follower for use in connection with my improvement. Hence I have illustrated a suitable device of this character (see Figs. 2 and 6), the same consisting of a follower member 20, with which is connected a spring 21, having a coil at its upper extremity, as shown at 22, from which two arms 23 extend downwardly and merge into horizontal parts 24, which pass through 10 openings in the opposite sides of the follower member, the extremities of these parts 24 extending into grooves 25 in the opposite sides of the box, just above the strips 18, which form the guides for my improved adjustable frame. The parts 23 of the spring are provided with rearwardly projecting arms 26, which may be grasped by the thumb and finger when it is desired to adjust the follower. By pressing inwardly on 20 these arms, the follower will be released, whereby it will be readily movable, while normally the tension is such as to cause the extremities of the member 24 to tightly engage the bottoms of the grooves 25, securely 25 retaining the follower in the adjusted position.

I claim:

1. A card-raising device for filing drawers, comprising in combination with the drawer, a frame slidable in the drawer below the cards, a rod journaled in the frame and provided with a crank arm, and a plate hinged to the frame and adapted to be acted on by the crank arm to lift the cards.
2. A device of the class described, comprising in combination with a filing drawer, a frame slidably mounted in the drawer below the cards, a frame-actuating rod journaled in the frame and extending through 40 the forward end of the drawer, the rod having a crank arm, a plate hingedly connected with the rear part of the frame and extending forwardly therefrom above the crank arm of the rod, whereby, as the rod is given 45 a partial rotation, the plate is actuated for card-raising purposes.
3. The combination with a filing drawer, of a frame located in the lower part thereof and longitudinally movable therein, the drawer having means for guiding and retaining the frame in place, a rod journaled in the frame and connected therewith to impart the longitudinal movement, the rod having a crank arm, and a plate liftably connected with the frame and adapted to be acted on by the crank arm of the rod as the latter is given a partial rotation.
4. A filing drawer for cards, a frame

longitudinally slidable in the lower part thereof, the sides of the drawer having guide 60 grooves and the frame having parts entering said grooves, a plate liftably connected with the frame, for card-raising purposes, and means connected with the frame for actuating the latter and imparting the lifting 65 movement to the plate.

5. The combination with a filing drawer, of a card-lifting device arranged therein, means longitudinally slidable in the lower part of the drawer and upon which the said 70 device is liftably mounted, and a longitudinally disposed rod journaled in the said means and provided with a crank arm for actuating the said device, the rod extending forward beyond the drawer. 75

6. The combination with a filing drawer, of means longitudinally slidable in said drawer below the cards, a card-raising device liftably mounted on said means, and a longitudinally disposed rod connected with 80 the said means for actuating the same, the rod being journaled in the said means and having a crank arm arranged to actuate the card-lifting device.

7. The combination with a filing drawer, 85 of a card-lifting device slidably mounted in the lower part of said drawer, and means extending beyond the forward extremity of the drawer and connected in operative relation with said device for moving the latter 90 both longitudinally and liftably.

8. The combination with a filing drawer, of means longitudinally slidable in said drawer below the cards, a card raising device liftably mounted on said means, and 95 a longitudinally disposed rod connected with the said means for actuating the raising device.

9. The combination with a filing drawer, of means longitudinally slidable in said 100 drawer below the cards, a card raising device liftably mounted on said means, and a longitudinally disposed rod connected with the said means for actuating the same, the rod having means thereon to engage and 105 lift said raising device.

10. The combination with a filing drawer of means longitudinally slidable in said drawer below the cards, a card raising device liftably mounted on said means, and 110 a member disposed longitudinally of the drawer and extending from the front of the drawer to the raising device for lifting the latter.

In testimony whereof I affix my signature. 115
WILLIAM E. WALKER.
